(57) CLAIM

The ornamental design for a front portion of a vehicle, toy, and/or replicas thereof, as shown and described.

DESCRIPTION

This application contains subject matter related to the following co-pending U.S. design patent applications: application Ser. No. 29/400,374, filed herewith and entitled "Front Portion of a Vehicle, Toy, and/or Replicas Thereof"; application Ser. No. 29/400,382, filed herewith and entitled "Radiator Grill for a Vehicle"; and application Ser. No. 29/400,392, filed herewith and entitled "Radiator Grill for a Vehicle".

FIG. 1 is a right, perspective view of a front portion of a vehicle, toy, and/or replicas thereof according to our design, the left, perspective view being mirror symmetrical; and, FIG. 2 is a front view thereof.

The broken lines are for illustrative purposes only and form no part of the claimed design.

1 Claim, 2 Drawing Sheets

FIG. 2
